UNITED STATES PATENT OFFICE.

RUDOLPH M. HUNTER, OF PHILADELPHIA, PENNSYLVANIA.

SPRINKLER-NOZZLE.

1,028,940.

Specification of Letters Patent. Patented June 11, 1912.

Application filed August 15, 1910. Serial No. 577,150.

To all whom it may concern:

Be it known that I, RUDOLPH M. HUNTER, a citizen of the United States, and a resident of the city of Philadelphia, county of 5 Philadelphia, State of Pennsylvania, have invented an Improvement in Sprinkler-Nozzles, of which the following is a specification.

My invention has reference to fire extinguishing sprinkler nozzles, and consists of 10 certain improvements which are fully set forth in the following specification and shown in the accompanying drawings which form a part thereof.

15 Heretofore it has been customary in certain fire extinguishing systems to employ sprinkler nozzles which automatically open and permit the discharge of water in the form of spray in case of an increase in temperature adjacent to the nozzle due to fire, the said system being largely employed in 20 warehouses and stores. In the nozzles heretofore in use, there has been considerable unreliability in their action and consequent 25 danger of loss to the owner or lessee of the building owing to the fact that where the nozzles have remained in sealed condition for a great period of time, the lever mechanism employed for holding the valve closed

30 becomes set and unresponsive when the fusible metal of the retaining link has been fused sufficiently to partly release the valve sufficiently to permit water to escape, and which, because of the sluggish action of the 35 lever mechanism, frequently becomes chilled and thereby prevents a full opening of the nozzle and with a consequent failure of the nozzle to produce its proper extinguishing effects. It is also frequently the case that

40 the lever mechanism of valves of the above character become set under the tension applied to them in use and which, especially in cases where considerable vibration of the building is present, tends to produce a leakiness in the valve which is objectionable and 45 in many cases a source of considerable loss because of injury to valuable goods stored below the nozzle.

The object of my invention is to provide 50 a construction of sprinkler nozzle which shall overcome the above objections of those heretofore in use, by being so made as to be

responsive the moment the fusible metal has been fused and so arranged as to operate under spring action to quickly separate the 55 two parts of the retaining link and permit a free discharge of the water from the sprinkler with absolute reliability, the spring action herein referred to further co-operating with the water for throwing the sealing devices out of the path of the water as soon as the fusible metal is sufficiently softened 60 to permit the unsealing of the nozzle in the manner above stated.

My improvements consist of certain devices hereinafter fully described for carrying out the above objects, and these improvements will be better understood by reference to the drawings in which:—

Figure 1 is an elevation of a sprinkler 70 nozzle embodying my invention; Fig. 2 is a plan view of the same; Fig. 3 is a sectional elevation of my improved sprinkler nozzle illustrating some modifications relatively to Fig. 1; Fig. 4 is a plan view of the 75 structure shown in Fig. 3; Fig. 5 illustrates a modification of the post and lever mechanism which may be employed; Fig. 6 is an elevation of the post; and Fig. 7 is a plan view of the main lever blank before being 80 bent up into shape.

A is the nozzle of the sprinkler and is provided at the top with the seat C and at the bottom with the screw threaded part B for attachment to the piping. This nozzle 85 is provided with upwardly extending arms D which terminate in a hub E, arranged directly above the orifice of the nozzle A.

G is the valve and this fits over the nozzle valve seat C, and is preferably recessed to 90 receive a disk of paper H to make a better sealing joint. The upper part of the valve G may be provided with an upwardly extending projection I centrally arranged.

More specifically referring to Figs. 1 and 95 2, J is a screw which works through a screw threaded aperture in the hub E, and the lower end of this screw is recessed to form a socket K. Formed integral or otherwise with the screw J is the distributor or spraying head L, which may be formed in the shape of a flanged disk provided with spirally arranged slots, the flange extending downward about the hub E, as shown, the 100

said distributor or spraying head receiving the water from the nozzle and causing it to be sprayed in all directions. The said distributor or spraying head L being integral with the screw J, acts as a means for adjusting the screw in the hub E to secure proper adjustment of the retaining mechanism for the valve G, to be now described. N is the main lever and is made of spring metal, such as sheet brass, and may be made from a blank of the shape shown in Fig. 7, the said blank consisting of the parts N' and N² in alinement, with an aperture N³ in the part N', and the said part N' having its free end reduced to form a shouldered part N⁴. When the parts N' and N² are bent upon the dotted lines in Fig. 7 and otherwise properly shaped, they constitute the lever structure shown in Fig. 1, which provides a 2-ply part adjacent to the valve and a 1-ply part N' as the free end. This lever N is so adjusted that the upwardly projecting portion I of the valve G is received in the orifice formed by the hole N³, the said orifice being closed at the top by the part N². The part N² is furthermore provided on its upper surface with a V-shaped notch extending across its width and to one side of the center of the aperture N³ so that said parts are somewhat out of alinement. O is a post and its lower end is made knife edged and received in the V-shaped groove N⁴ of the lever N, and its upper end is reduced in width to form the centering pin O' which is received by the recess K in the adjusting screw J. The free end of the lever N formed by the part N' is bent upward approximately on a line with the top of the sprinkler nozzle as a whole and is retained in sealed position by means of the fusible link P which comprises the two metal plates P' and P² lying face to face and secured together by a fusible solder P³, the plate P' having an orifice which fits over the end N⁵ of the lever N, and the plate P² having an orifice which fits over a central upwardly extending pin M of the screw J and distributor head L, said retaining link P holding the mechanism formed by the lever N and post O in proper position to hold the valve G tightly upon its seat C. It will be further observed that this lever N is made with great elasticity, so that when sealing the sprinkler nozzle in condition for use, the free end of the said lever N may be forced in toward the pin M $\frac{1}{2}$ to $\frac{3}{4}$ of an inch before it is locked, and hence it will be understood that no matter how long the nozzle remains in sealed condition, the spring action of the lever N will be so great that when the fusible metal is fused the outward springing of the free end of the lever N will instantly separate the plate P' from the plate P² and this action

will be so quick that there will be no possibility of the fusible metal being chilled by the water before the parts are fully liberated. 65

The free spring action of the lever N prevents the valve retaining mechanism from becoming set under vibration or otherwise and which would cause a leaky condition of the valve, and consequently, sprinkler nozzles of the character herein described cannot become leaky, by merely remaining in sealed condition for a long period from lack of necessity for use by fire; consequently the valves will be always in highly sensitive condition for immediate response in case of necessity and as the spring parts will not be over strained and set there will be large elimination of a possible damage to merchandise by leaky condition precedent upon a failure of the valve retaining mechanism indefinitely holding the valve tightly upon its seat, or compensating for a reduction in the thickness of any packing H which may be employed between the valve and the valve seat. 70 75 80 85

From the construction of the spring lever N shown, it will be observed that the lower part is very rigid where resistance is necessary, whereas the upper part is quite flexible. By the extension of the part N² part way up upon the part N' to some distance beyond the post O, it is evident that a leaf spring effect is produced, so that there is no danger of overstrain upon the spring part N' near the points of greatest resistance. 90 95 100

When the nozzle has been operated under the action of heat to permit the flow of the water, the fusing of the fusible metal P³ permits a quick spring action of the free end of the lever N, which throws the plate P' away from the plate P² and out of the path of the flowing water so as not to interfere with its distribution, and at the same time the inertia given to the lever N by this releasing action causes it to rotate about the projection I of the valve as a center, with the result of throwing the plate O laterally out of the path of the water and of applying a pressure to the upper part of the valve in an opposite direction in the act of liberation which causes the water to throw the valve laterally from its seat and out of the direct path of the water in reaching the distributor. In this manner, the distributor acts in a most responsive way to provide the proper spray for the protection of the goods. 105 110 115 120

In the modification shown in Figs. 3 and 4, the general construction is the same, but in this case, instead of employing a blank bent upon itself to form the lever N, it is formed of two parts N' and N⁶ riveted together by the downwardly projecting part I' 125

which seats in the recess F' in the top of the valve G. The operation of this lever is the same as in the case of Fig. 1. In the modification, the distributor or spraying head L is provided with a series of upwardly projecting parts M' adjacent to its perimeter over which the plate P² may be hooked in place of said plate being over a central pin M, as in Fig. 1. In the modification, the tension of the lever N, because of the connection with the distributor head, will cause the said distributor head to be locked in adjusted position.

In the construction shown in Fig. 5, the projection I of Fig. 1, or I' of Fig. 3, is formed as a ball I², said ball resting at the bottom in the socket F' of the valve piece and having its top engaging the aperture N³ of the lever. In place of the ball any other shaped member may be introduced.

I have shown the invention in the form which embodies simplicity and cheapness of construction, and while the said details are preferred, I desire it to be understood that I do not limit myself to the details, as these may be modified without departing from the spirit of the invention.

Having now described my invention what I claim as new and desire to secure by Letters Patent, is:—

1. In a sprinkler nozzle, the combination of the body having a valve seat, with a valve piece therefor, a two part mechanism interposed between the body and the valve piece to hold said valve piece upon the seat one member of said mechanism consisting of a freely acting spring lever and the other of an oblique strut, an adjustable abutment screw to adjust the position of the oblique strut a spraying or distributing member carried by the body in line with the valve seat and having a central pin at its top, and a fusible member for normally retaining the spring lever under heavy tension connected at one end to the spring lever and at the other to the pin of the distributing member, the parts being so constructed that upon the release of the spring lever by the fusible member it will forcibly act to fully disrupt the fusible member before being reached by the water.

2. In a sprinkler nozzle, the combination of the body having a valve seat, with a valve piece therefor, a mechanism interposed between the body and the valve piece to hold said valve piece upon the seat one member of said mechanism consisting of a freely acting spring lever formed of spring sheet metal made double-ply for a portion only of its length and adjacent to the valve end and single-ply at its free and longer end, and a fusible member for normally retaining the single ply end of the spring lever under heavy tension, the parts being so construct-

ed that upon the release of the spring lever by the fusible member it will forcibly act to fully disrupt the fusible member before being reached by the water.

3. In a sprinkler nozzle, the combination of the body having a valve seat, with a valve piece therefor, a mechanism interposed between the body and the valve piece to hold said valve piece upon the seat one member of said mechanism consisting of a freely acting spring lever formed of spring sheet metal made double-ply for a portion only of its length and adjacent to the valve end by being folded upon itself nearer one end than the other and single-ply at its free and longer end, and a fusible member for normally retaining the spring lever under heavy tension, the parts being so constructed that upon the release of the spring lever by the fusible member it will forcibly act to fully disrupt the fusible member before being reached by the water.

4. In a sprinkler nozzle, the combination of the body having a nozzle, a valve therefor, an adjusting abutment screw, a two-part mechanism interposed between the abutment screw and the valve one of which parts consists of a long spring lever having its connection with the valve and other member of the mechanism out of alignment and made two-ply for part of its length at 95 and adjacent to said connection and in one of which plies is formed a seat for the other member of the mechanism and in the other of which plies is provided a seat directed toward and acting upon the valve, and a link having a fusible element between its ends and having one end supported from the body and the other end engaging the free end of the spring lever and normally maintaining it under great tension.

5. In a sprinkler nozzle, the combination of the body having a nozzle, a valve therefor, an adjusting screw abutment on the body directed toward the nozzle, a two-part mechanism interposed between the abutment screw and the valve one of which parts consists of a long spring lever having its connection with the valve and other member of the mechanism out of alignment but close to one end and made of a strip of 115 spring sheet metal folded upon itself to form a two-ply structure one ply having a transverse groove for the other member of the mechanism and the other ply having a recess directed toward the valve and out 120 of alignment with the groove, and a link having a fusible element between its ends and having one end supported from the body and the other end engaging the free end of the spring lever and normally maintaining it under great tension.

6. In a sprinkler nozzle, a body part having a valve-seat, a valve therefor, an adjust-

ing abutment screw having a distributer head integral with it so that they move as a unit, a mechanism between the abutment screw and valve and having a lever member 5 formed with a long spring arm normally under great tension, and a fusible member connecting the free end of the spring arm of the mechanism with the axis of the abutment screw and distributer head so that the

screw may be adjusted while the spring is 10 held by the fusible member.

In testimony of which invention, I hereunto set my hand.

R. M. HUNTER.
